UNITED STATES PATENT OFFICE.

HUGH J. MONTGOMERY, OF DES MOINES, IOWA.

TELEPHONE-DIRECTORY.

1,099,882.

Specification of Letters Patent. Patented June 9, 1914.

Application filed February 26, 1912. Serial No. 680,115.

To all whom it may concern:

Be it known that I, HUGH J. MONTGOMERY, a citizen of the United States, residing at Des Moines, in the county of Polk and State of Iowa, have invented a certain new and useful Telephone-Directory, of which the following is a specification.

The object of my invention is to provide a spring actuated roller made of few parts that are inexpensive in construction and that may be readily and easily assembled and that is provided with simple and inexpensive means whereby a telephone directory strip of paper, cloth or other suitable material may be quickly and easily attached to or detached therefrom, which spring roller will automatically wind up the directory strip when the latter is released.

A further object is to provide an improved bracket for supporting the roller so arranged that it may be quickly and easily applied to a telephone instrument by the simple operation of removing the receiving mouth piece of a telephone instrument, then placing the bracket adjacent to the telephone instrument and returning the mouth piece to position for firmly clamping the bracket.

A further object is to provide improved means for stopping the winding movement of the directory strip upon the spring roller when the directory strip is fully wound up, which means is so arranged that it may be connected to the directory strip quickly and easily and which is also so arranged that the lower end of the strip will not be torn or worn out by the repeated rolling up of the strip upon the spring roller.

My invention consists in certain details, in the construction, arrangement and combination of the various parts of the device, whereby the objects contemplated are attained, as hereinafter more fully set forth, pointed out in my claims and illustrated in the accompanying drawings, in which:

Figure 1 shows a front elevation of a part of a telephone instrument having my improved directory applied thereto and shown in its rolled up condition. Fig. 2 shows a side elevation of same. Fig. 3 shows a front view of the telephone directory embodying my invention detached from a telephone instrument, and also shows the directory strip partially unwound from the roller. Fig. 4 shows a detail, perspective view of the roller

supporting bracket. Fig. 5 shows an enlarged, detail, transverse, sectional view through the spring roller. Fig. 6 shows a front elevation of the spring roller and its supporting bracket with the directory strip detached. Fig. 7 shows a front view of the upper portion of a directory strip designed to be attached to my improved spring roller. Fig. 8 shows a horizontal, sectional view through the bracket and spring roller as will appear looking downwardly, and Fig. 9 shows a longitudinal, sectional view of the lower end portion of the directory strip and the rod of the handle device therein.

Referring to the accompanying drawings, the bracket for supporting the spring roller is formed of a single piece of resilient spring metal and comprises a straight flat body portion 10 having at the central portion of its upper edge an arm 11 having a circular opening 12 therein. The arm 11 is formed flat and is designed to be placed flat against the face of the receiver portion of a telephone. This part of a telephone is indicated by the numeral 13. The circular opening 12 is of a size and shape to receive the screw threaded portion of the transmitter mouth piece 14 of the telephone which, when screwed into position in the ordinary way, will bind the arm 11 tightly against the face of the telephone. At the ends of the body portion 10 are two forwardly extended arms 15 and 16 at right angles to the body portion 10 and which is provided with an angular opening 17. The said arms 15 and 16 being made of spring metal may be readily and easily sprung apart a slight distance and will then return to their normal positions at right angles to the body portion 10.

The spring roller comprises a shaft 18 having angular ends 19 which are designed to fit into the angular openings 17. The central portion of the shaft is preferably smooth and round and near the end portions of the shaft I have rotatably mounted two disks, each of which comprises a body portion 20, and an outwardly extended flange 21. Each of said body portions 20 is provided on its periphery with an annular groove 22 for purposes hereinafter made clear.

Coiled upon the central portion of the shaft 18 between the body portions 20 is a spring 23 having one end fixed at 24 to the shaft 18 and the other end fixed to one of

the body portions 20 at the point indicated by the numeral 25 in Fig. 8. The body portion of the spring roller is formed of a single piece of spring sheet metal of substantially cylindrical form and indicated by the numeral 26. The edges of the roller thus formed stand spaced apart from each other, as clearly shown in Fig. 6, and one edge is provided with a series of pointed lugs 27 arranged on the same curvature as the body portion of the cylinder, as clearly shown in Fig. 5. The end portions of the cylinder 26 are provided with inwardly extended portions 28. These inwardly extended portions 28 are designed to coat with the annular grooves 22 in such a manner that when the cylinder 26 is sprung apart it may readily be placed with the parts 28 in the grooves 22 and then the resiliency of the metal will draw the parts together, thus firmly holding the cylinder 26 to both of the body portions 20 and thereby preventing spreading movements of the body portions 20 toward or from each other. This yielding engagement between the cylinder and the body portions 20 also serves to firmly connect said parts in such a manner that they will all rotate in unison on the shaft 18.

Obviously the parts just described may be readily and easily assembled on the shafts 18 without the necessity of using rivets, bolts or similar fastening devices. Then the arms 15 and 16 may be sprung apart to thereby permit the angular ends of the shafts 18 to enter the angular openings 17. Then when the arms 15 and 16 spring together all of said parts will be firmly united as required for use.

The directory strip is formed of a single piece of paper, fabric, or the like indicated by the numeral 29. At its upper end are a number of slots 30 and its lower end is formed into a loop 31, as shown in Fig. 9. I attach the directory sheet to the spring roller by simply inserting the slotted end thereof in the open side of the cylinder and then permitting the projections 27 to pass through the slots 30, whereupon the remainder of the directory sheet is wound upon the spring roller in the ordinary manner.

At the bottom of the directory sheet, I have provided a handle and stop device comprising a flat sheet metal body portion 32 having upwardly extended arms 33 at its ends designed to project beyond the side edges of the directory sheet. These arms 33 are provided with loops 34 in which I have detachably mounted a rod 35. This rod is extended through the loop 31. The said arms 33 are so arranged and shaped that when the directory strip is rolled up by the spring roller they will strike upon the arms 15 and 16 of the bracket and thus limit the rolling up movement of the directory strip and at the same time receive all of

the shock or jar, thus preventing the unnecessary wear or strain upon the directory strip that might otherwise be occasioned by means of stop devices or handles fixed to the directory strip by being inserted through openings formed therein. With this construction there is obviously slight probability of tearing the directory strip or roller.

In practical use, it is obvious that my improved telephone directory may readily and quickly be applied to a telephone instrument in a firm and secure manner without any fastening devices other than are ordinarily provided on telephone instruments that have detachable screw threaded transmitter mouth pieces. The spring roller is of extremely simple construction and the parts may all be readily assembled without the use of bolts, rivets, or other fastening devices. After the parts of the spring roller are assembled, the roller and shaft may be readily and easily inserted in the bracket and there firmly held merely by the resiliency of the arms 15 and 16 and by having the squared ends of the shaft inserted in the squared openings of the said arms.

The directory strip is of extremely simple and inexpensive construction and has no fastening devices or the like applied to it. It is simply provided on one end with a number of perforations and the other end is doubled over and pasted or sewed together to form a loop. The upper end of the directory strip is made readily and easily detachable by simply inserting the end in the open side of the roller and permitting the lugs 27 to enter the slots 30. Then it is rolled up in the ordinary way and the lower end is connected to the handle or stop device by inserting the rod 35 through the loop.

The entire device is constructed to be used without a ratchet device of any kind which is unnecessary for the reason that when the operator desires to read the matter upon a directory strip he simply grasps the handle 32 and pulls the directory strip out until the desired information is attained. He then releases the handle and the directory strip automatically rolls up to its closed position, as shown in Fig. 1.

Before placing the directory strip upon the spring roller the operator simply turns the roller by hand a suitable number of revolutions until the spring 23 is put under a proper tension. He then attaches the directory strip and thereafter each time that the strip is pulled out a certain additional amount of power is stored in the spring which is sufficient to automatically rewind the directory strip when the handle is released. The flanges 21 on the spring roller serve as guides to hold the directory strip firmly in line and the arms 33 at the ends of the handle or stop device, when they engage the arms 15 and 16, will cause the di-

rectory strip to stand straight upon the roller if there should, at any time, be a tendency for it to wind up unevenly.

I claim as my invention:

1. A device of the class described, comprising a bracket formed of a single piece of spring metal and comprising a body portion, an arm extended upwardly from the body portion and designed to be attached to a telephone, arms at the ends of the body portion extended outwardly and provided with angular openings, said arms being capable of being sprung apart and of returning to normal position extending straight forwardly from the body portion, a shaft of such length that it may be conveniently sprung between the arms of the body portion and having angular ends designed to fit into the angular openings of said arms, two disks loosely mounted upon the shaft adjacent to said arms, a hollow cylinder detachably connecting said disks and designed to hold said disks spaced apart from each other and adjacent to said arms, and a spring within the cylinder wound upon the shaft and having one end attached to one of said disks and the other end attached to the shaft, for the purposes stated.

2. In a device of the class described, the combination of a bracket designed to be secured to a telephone, a shaft supported in said bracket, a spring actuated roller comprising two end pieces, each being loosely mounted upon the shaft and each being provided with an inwardly projecting cylindrical portion provided with an annular groove on its periphery and also provided with an outwardly projecting flange, and a cylinder made of spring material with its side edges spaced apart from each other and its end portions projected inwardly to enter the grooves on said end portions, said parts being so arranged that the said spring cylinder will serve to hold the end pieces firmly in position so that they will both rotate in unison on the shaft, a spring attached at one end to the shaft and at the other end to one of said end pieces, said spring being contained within said cylinder and surrounding the shaft.

Des Moines, Iowa, February 16, 1912.

HUGH J. MONTGOMERY.
